UNITED STATES PATENT OFFICE

JAMES A. B. LOVETT, OF PITTSBURGH, PENNSYLVANIA, ASSIGNOR TO THE KOPPERS COMPANY, A CORPORATION OF DELAWARE

PUSHER RAM FOR COKE OVENS

Application filed April 12, 1927. Serial No. 183,093.

My invention relates to pusher rams for coke ovens of the horizontal type.

My invention has for one of its objects to provide a pusher ram of such form and construction that it will operate to remove a charge of coke from a coke oven with minimum force applied thereto.

A further object of my invention is to provide a pusher ram for coke ovens by means of which coke may be removed therefrom with minimum formation of coke breeze and broken coke.

In the operation of pushing coke ovens as usually practiced, the pusher rams that are usually employed are provided with a vertical face which simultaneously engages the entire end surface of the charge of coke. It is a well-known fact that the greatest resistance to be overcome by the pusher ram is at the bottom of the oven, by reason of the roughness of the oven floor and because the weight of the charge is supported by the floor.

In case the charge of coke has a tendency to stick in the oven, it is necessary to advance the ram a considerable distance against the entire end of the charge before the coke begins to move. The result is that considerable coke is crushed and coke breeze formed. The crushing of the coke causes a certain portion of the coke body to engage the side walls of the oven and thus add to the resistance caused by the weight on the oven floor. The resistance caused by the loose coke increases approximately with the distance from the top of the column.

I have found that, if sufficient pressure be applied to the bottom layer of coke before any pressure is applied to the remainder of the coke, the entire charge may be moved with materially less power applied to the pusher ram. For example, a certain force has been required to push an oven with the ordinary pusher ram having a straight vertical face. When a block was employed at the base of the oven, to engage the bottom layer of coke in advance of the remainder of the face of the ram head, a very much smaller force was required to move the coke.

In accordance with my invention, I pro-

vide a pusher ram with a head having a bottom portion that projects in advance of the remainder of the face for engaging the coke. In a modified form of the invention, the face of the pusher ram head is arranged in steps that are spaced approximately in accordance with the difference in the pressures to be overcome at the various levels in the charge of coke, in case the charge tends to stick in the oven and loose coke is formed.

Reference may now be had to the accompanying drawings, in which

Figure 1 is a view, in vertical section, of a portion of a coke-oven battery and associated apparatus embodying my invention the apparatus being shown in elevation;

Fig. 2 is a side elevational view of a pusher ram embodying my invention, parts being broken away; and

Fig. 3 is a similar view of a modification. Reference may now be had to Fig. 1, in which a coke-oven battery, only a portion of which is shown, comprises a series of coke ovens 2, through one of which the sectional view is taken. The coke oven 2 is provided with a floor 3 and with a top 5, through which extends the usual offtake opening 6 that is connected by an ascension pipe 7 to a collecting main 8. The oven 2 is also provided with a detachable door 9, which is removed when the charge of coke indicated at 10 is ready to be pushed.

A pushing machine 12, which operates on rails 13 that are parallel to the battery, carries a pusher ram 14. The pusher ram comprises a relatively long bar 15 that is provided with rack teeth 16 whereby the pusher ram may be driven by an electric motor 17 and suitable gear mechanism 18. The bar 15 is mounted for longitudinal movement on rollers 19. The pusher ram is provided with a head 20 for engaging the coke during the pushing operation. The pusher machine 12 also carries the usual leveller bar 21, the details of which form no part of the present invention.

Reference may now be had to Fig. 2, which is an enlarged view of certain portions of the pusher ram 14. The ram is provided with a supporting shoe 22, the details of which

constitute the subject-matter of a copending application. The head 20 of the pusher ram is provided at its lower portion with a projecting portion 23 having a vertical face 24 that is offset from the vertical face 25 of the main portion of the head 20.

The face 24, the height of which is small relative to that of the face 25, extends in advance of the face 25 by a distance that is approximately that necessary to secure the movement of the bottom layer of coke simultaneously with the engagement of the remainder of the charge by the face 25. By way of example, the height of the face 24 may be about twelve inches and the faces 24 and 25 may be spaced a similar distance.

The lower portion of the vertical face 24 is constituted by a swinging plate or "flapper" plate 26 that is pivotally mounted at 27 and is preferably provided with a counter-weight 28. The flapper plate is arranged to move forwardly with respect to its vertical position but is rigidly held against any rearward movement from such position.

In the operation of the ram illustrated in Figs. 1 and 2, it being assumed that the door 9 of the coke oven has been removed, the ram is advanced by the motor-driven gear mechanism 18 from the position in which it is illustrated in Fig. 1 to engage the charge of coke. The face 24 engages the bottom portion of the charge and the force of the ram is concentrated thereon. When the ram is moved to advance the projection 23 into the coke, the latter may begin to move somewhat before or about simultaneously with the engagement of the face 25 with the end of the charge.

The entire charge then moves forward as a body and there is no tendency for the top portion of the charge to move in advance of the bottom portion. Accordingly, the body of coke moves through the coke guide on the coke side of the battery without the spillage that accompanies the pushing operation as in present practice. By reason of the fact that the engaging faces are vertical, even though they are offset the one from the other, there is no component of force tending to either cause the coke to be lifted in the oven or to cause the ram to exert an abnormal force upon the floor of the oven.

When the charge of coke has been completely removed, the ram is returned by reversing the driving mechanism. During the return of the ram, the flapper plate 26 swings readily to permit any loose coke to pass thereunder in order that it may not be dragged along the floor of the oven. The ram is then returned to its illustrated position in readiness for the succeeding operation.

In the modified form of pusher head 30 shown in Fig. 3, the face 24 is provided and in addition, faces 31, 32 and 33 are arranged in steps. This arrangement is provided for

the purpose of following approximately a line representing the resistance offered by the charge of coke at the various levels when the coke is crushed.

It will be appreciated that, in the case of loose coke, the resistance of the coke from the upper surface to the vicinity of the bottom of the charge will vary substantially with the weight of the charge and that the resistance of the bottom surface of the coke will be materially greater since the weight of the entire charge is supported by the floor of the oven. Accordingly, a curve which represents the resistances will be substantially a straight line for the upper portion of the charge and there will be an abrupt bend in the curve for the change in resistance at the bottom of the charge. The vertical faces of the pusher head in Fig. 3 have been arranged to follow approximately the curve described above. It will be appreciated, however, that conditions will not be exactly duplicated in the various ovens to be pushed and that only an approximation is possible.

When the ram constructed as in Fig. 3 is employed in pushing a coke oven under normal conditions, the operation is substantially similar to that previously described in connection with the ram of Fig. 2 in that the force is concentrated at the bottom of the oven and that movement of the charge may begin more or less independently of the engagement of the faces above the face 24. However, when the charge sticks in the oven and coke is crushed, the various engaging faces engage the coke at intervals that correspond substantially to the differences in resistance to be encountered at the various levels engaged thereby. Accordingly, when the entire head is engaged, the horizontal faces support the loose coke and spillage is prevented.

It will readily be appreciated that the amount of coke breeze resulting from the operation of a pusher ram of my invention will be materially less than that when the pusher head is not shaped to some degree in accordance with the resistances to be encountered.

I have provided an improved pusher ram by means of which pressure is applied initially to the bottom of the charge of coke, the region that offers the greatest resistance. The charge of coke is placed in motion with the least damage to the structure of the coke and with the minimum force necessary to effect the movement of the coke. The shapes of the engaging faces are such that there are no vertical components of the force applied by the pusher ram which tend to cause either the coke to rise against the roof of the oven or the ram to bear heavily upon the floor of the oven.

My invention may be embodied in various forms and it is not desired to limit it to the

specific embodiments shown and described herein. The scope of my invention is limited only by the appended claims.

I claim as my invention:

- 5 1. A pusher ram for coke ovens comprising a head having a plurality of vertical faces for engaging a charge of coke, said vertical faces being offset extending rearwardly from the bottom face.
- 10 2. A pusher ram for coke ovens having vertical portions for first engaging the charge of coke to be pushed in the region that normally offers the greatest resistance and for subsequently engaging other portions of the charge.
- 15 3. The method of pushing coke from a horizontal coke oven which comprises first applying pressure to a vertical face of the bottom portion of the charge of coke where the resistance is greatest and then applying pressure to other portions of the charge.
- 20 4. A pusher ram for coke ovens comprising a vertical bottom portion for engaging a charge of coke in advance of the remaining portion of the head and a substantially vertical upper portion horizontally offset from said bottom portion.

In testimony whereof, I have hereunto subscribed my name this 11th day of April, 30 1927.

JAS. A. B. LOVETT.
